UNITED STATES PATENT OFFICE

LE ROI E. HUTCHINGS, OF BUFFALO, NEW YORK, ASSIGNOR, BY MESNE ASSIGNMENTS,
TO REMINGTON RAND INC., OF NEW YORK, N. Y., A CORPORATION OF DELAWARE

RECORD CARD HOLDER

Application filed May 10, 1926. Serial No. 107,961.

This invention relates to record card holders and relates more specifically to holders in which the corners of record cards are engaged to maintain said card in convenient reference 5 position.

In record card holders heretofore used, the visible area of the record card has been appreciably reduced by the devices for holding the record card onto the support member. 10 Also the holding devices do not conveniently receive a signal. Some holding devices employ a considerable amount of celluloid which materially increases the cost of the devices.

An object of this invention, therefore, is 15 to provide a record card holder in which a maximum visible area of the record card is obtained.

A further object of the invention is to provide a device of the class described which will 20 readily support a signal device.

A still further object of the invention is to reduce the amount of celluloid required to a minimum or entirely avoid its use, thus reducing the cost of manufacture of the card 25 holders; also to improve record card holding devices in other respects hereinafter specified and claimed.

Reference is to be had to the accompanying drawings forming a part of this specification, in which,

Fig. 1 is a front elevation of one form of my improved record card holders.

Fig. 2 is a front elevation of another form of my record card holder.

Fig. 3 is a front elevation of another of my record card holders, with a modified supporting device for the holder.

Fig. 4 is a perspective view of a corner pocket for one of my card holders.

Fig. 5 is a fragmentary front elevation of a corner of the card holder shown in Fig. 1 before assembly.

Fig. 6 is a transverse sectional view through a corner pocket taken on the line 6-6 of

Fig. 2.

Fig. 7 is a fragmentary front elevation of a corner of the card holder shown in Fig. 2 before assembly.

Fig. 8 is a form of the card holder shown in Fig. 3 with a modified indexing device.

Referring to the drawings in detail, my improved record card holder consists preferably of a body portion or holder card which may be of any suitable flexible material such as heavy kraft paper. This holder card 10a or 10b may be provided at the top with a plurality of diagonal slots or openings 11 for the purpose of receiving the upper corners of a record card 12. In order to mount or receive the lower corner of card 12 on the 60 holder card, a piece of celluloid preferably transparent having a plurality of triangular-shaped folds 13 may be attached to the lower corner of card holder 10a by any suitable means such as a stitch or staple 14, or the like 65 as shown in Fig. 3. This celluloid fold 13 forms a pocket 15 into which the lower corner of record card 12, Fig. 2, may be received, and a signal 16 of any desired construction or color may also be received in said pocket 70 15 in order to indicate activity of said record card 12.

By suitably shaping the card holder before assembly I am enabled to entirely avoid the use of celluloid and therefore considerably 75 reduce the cost of manufacturing my record card holder devices. As shown in Figs. 5 and 1, the card holder 10 may be cut out to form a triangular shaped lug or pocket member 17, said lug having bend lines 18 and 19. In order to assemble the pocket, the lug 17 is bent about lines 18 and 19 to form a pocket 20 on each side of the holder card 10, said pockets being preferably secured in position by a stitch or staple 21. Thus it is seen that 80 the pocket is entirely formed integral with and composed of the kraft paper card holder 10.

When it is desired to attach a record card 12 to only one side of a card holder 10b, Figs. 90 2, 6, 7, the pocket member 22 may be so constructed that the pocket at the front of the card holder is composed of a double thickness of kraft paper for reinforcing purposes. Before assembly the card holder 10b will be 95 cut out as shown in Fig. 7 to form two triangular shaped lugs or pocket members 23 and 24. The lug 23 will have bend lines 24a and 25, while the lug 24 will have a bend line 26. To assemble, lugs 23 and 24 are bent about 100

bend lines 25, 26 and 24a so as to form the double reinforced pocket 22, the latter being attached firmly to the card holder 10b by means of staple 27.

5 The card-holding device may be made self-indexing or visibly indexing by different ways such as by forming a cut-out portion 28 along the bottom edge of the record card 12, said portion 28 forming an opening through which 10 can be seen words or other legends 29 printed on the bottom edge of the holder card 10b. By forming a tab 30 on the bottom of card holder 10c, Fig. 8, I am enabled to use a record card 12a of standard rectangular shape 15 since the index legends 31 may be printed on said tab 30 and will be visible below the bottom edge of the record card 12a.

The card holders, 10, 10a, 10b and 10c may be supported from slides or other card supports in a variety of ways such as by attaching a stiffening strip or spacing bar along the top edge of the card holder 10 by means of staples 33, Fig. 1. In this case a bend line 25 may be formed in the card holder 10 adjacent strip 32 by a series of slots or openings 34. The ends of the strip 32 then form tongues 35 for insertion under suitable flanges of a slide support so that the card holders 10 are maintained in overlapping position with the strips 32 in abutting position, edge to edge.

As shown in Fig. 2, metal or other hinge clips 36 may be attached to the top of card holder 10b by suitable fastening tongues or rivets 37. The clips 36 may then be pivotally mounted on suitable pins not shown, these pins being attached to any desired supporting member so as to maintain the card holder 10b in convenient overlapping reference position.

10 As shown in Figs. 3 and 8, outstanding tongues 38 may be formed at the top of the card holder 10a, these tongues being adapted to be received in suitable slots or flanges on a supporting slide not shown. In this case 15 the card holder 10a would be supported or suspended from the tongues 38 in such a way that the cards are in overlapping reference position, as is well known in the art.

I would state in conclusion that while the 20 illustrated examples constitute a practical embodiment of my invention, I do not limit myself precisely to the ideas herein illustrated and described, since manifestly the same can be considerably varied without departing 25 from the spirit of the invention as defined in the appended claims.

I claim as my invention:

1. In an index or file, a holder member for record cards, means connected to one marginal edge of said member for detachable engagement with a support, and for spacing said holder member with a free marginal portion in visible relation with similar marginal portions of adjacent holder members, a U-shaped pocket-forming member embrac-

ing the corner portion of said holder member at each end of the free marginal portion thereof, and a fastener engaging the ends of each pocket-forming member and the edge of said holder member, said pocket-forming 70 members providing record card corner receiving pockets at opposite sides of the holder member.

2. In an index or file, a holder member for record cards, means on one marginal portion of said holder member for hingedly connecting said member in detachable engagement with a support, and for spacing said member from adjacent members on the support so that a free marginal portion thereof is visible, projections integral with the free marginal portion of said member at the end portions thereof, each of said projections having a pair of sections, said sections overlying the opposite sides of a corner portion of said holder member and cooperating therewith to form a card corner receiving pocket on each side of said holder member, and a staple extending through said sections of said projection and said holder member 90 for securing said sections to said member, said staples being adapted to hold record cards received in said pockets against lateral displacement.

3. In an index or file, a holder member for record cards, means on one marginal portion thereof for detachable engagement with a support to hingedly mount said holder member thereon in overlapping relation with adjacent holder members and with a free marginal portion exposed in visible indexed relation, a U-shaped pocket-forming member embracing the free corner portion of said holder member at each end of the free marginal portion thereof, a staple extending 105 through the ends of each pocket-forming member and the edge of said holder member for securing said members in assembled relation to form pockets at the opposite sides of said holder member, record cards detachably received on opposite sides of said holder member having the corner portions engaged in said pocket-forming members, the first-mentioned marginal edge of said holder member being formed to engage the opposite edges of said record cards and retain them in engaged relation in said pocket-forming members.

4. In an index or file, a holder member for record cards, means on one marginal portion thereof for detachable engagement with a support to hingedly mount said holder member thereon in overlapping relation with adjacent holder members and with a free marginal portion exposed in visible indexed relation, a U-shaped pocket-forming member embracing the free corner portion of said holder member at each end of the free marginal portion thereof, a staple extending 120 through the ends of each pocket-forming

member and the edge of said holder member for securing said members in assembled relation to form pockets at the opposite sides of said holder member, record cards detachably received on opposite sides of said holder member having the corner portions engaged in said pocket-forming members, said record cards and holder being formed intermediate the pocket-forming members to provide a portion on each holder in adjacent visible relation with a portion of said card, to visibly index both the card and holder.

LE ROI E. HUTCHINGS.
